PRODUCT FOR COVERING HIGHWAY JOINTS

William C. Ferguson, St. Louis, Mo.

Application November 15, 1934, Serial No. 753,147

2 Claims. (Cl. 94—18)

This invention relates to a method of covering highway joints and the like, and also to the product of said method, and with regard to certain more specific features, to a mending tape for sealing joints and cracks in roadways and the like.

Among the several objects of the invention may be noted the provision of economical means for sealing either new expansion joints or old contraction cracks in highways and the like; the provision of means of the class described which is particularly applicable to concrete and asphalt highways; the provision of means of the class described which will accommodate expansion and contraction of the joint; the provision of means of this class which may be pre-fabricated at a manufacturing establishment and then applied in the field in straight or curved forms with no specialized equipment; the provision of means of this class which will not slip and become detached by the action of traffic, but which will improve with age and with traffic conditions. Other objects will be in part obvious and in part pointed out hereinafter.

The invention accordingly comprises the steps and sequence of steps, the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a longitudinal section of the certain fabric employed in the invention;

Fig. 2 is a view similar to Fig. 1 showing that the fabric has been impregnated with asphalt;

Fig. 3 is a view similar to Fig. 2 showing that the fabric has had a wearing surface applied thereto;

Fig. 4 is a view similar to Fig. 3 showing that the fabric has had the bottom side scraped to condition it for use;

Fig. 5 is a longitudinal section showing the assembly for shipment of two pieces of the product, and showing at the left the same being torn apart prior to application;

Fig. 6 is a section of an expansion joint showing my protective material applied thereto, said section being taken on line 6—6 of Fig. 7; and,

Fig. 7 is a plan view on a reduced scale showing my protective material applied to an expansion joint.

Similar reference characters indicate corre-

sponding parts throughout the several views of the drawing.

It is known that concrete and like highways are laid with expansion joints formed at intervals laterally and along the center of the highway. 5 These are what may be called predetermined expansion joints. Asphalt highways and old concrete highways also have spontaneously formed therein contraction joints which take the form of cracks. Whether the expansion joints are regular or irregular, predetermined or spontaneous, they present the problem of a recess in which moisture collects and undermines the foundation of the roadway.

Heretofore, these joints have had asphalt or the like poured into them. This procedure is not always satisfactory, because if the asphalt is poured while the roadway is cold, it hardens and remains in the upper regions of the joints, and upon warming settles down irregularly to again form a recess for moisture. Furthermore, the working of the joints upon heat and cooling tends to work openings in the asphalt which has been poured into the joint. Thus disintegration and decay set in.

In the case of new concrete highways, flexible metal sheaths have been proposed and used in the joints. These are inserted upon laying the highway. It is obvious, however, that this method is not applicable to spontaneous cracks, or 30 to old highways, nor is it successful in the case of asphalt highways in general. In any case it is complicated to apply and also costly.

My present invention provides an economical, quick and clean means for sealing the joints 35 against seepage, the said means remaining in its original position and improving in its functions with age.

Referring now more particularly to Fig. 1, there is shown at numeral 1 a layer of canvas duck 40 cloth, preferably of about twelve to fourteen ounces in weight. This material is cut into strips of suitable width, depending upon the class of expansion joints to which it is to be applied. For instance, widths of two, four, six, eight 45 inches, etc. are suitable. It is to be understood that while canvas duck has been found to be a suitable fabric for this use, that other equivalents of this fabric may be used.

The fabric base is saturated with asphalt 3, 50 as shown in Fig. 2, the same covering both faces of the fabric and penetrating all of the interstices. An asphalt of high melting point and of low penetration value is used which will withstand the abuse of traffic and weather conditions.

Next, the asphalt-impregnated fabric 1, 3 has an upper surface applied thereto composed of more of said asphalt but admixed with trap rock, as shown at numeral 5 (Fig. 3).

5 The layer 5 is preferably only thick enough to provide a wearing surface which will protect the fabric from traffic wear. It is preferably composed of fifteen to twenty per cent asphalt and eighty-five to eighty per cent of trap rock. The 10 asphalt in the upper layer 5 and the asphalt impregnation of the fabric 1 intermingle and form a bond. The layer 5 forms a wearing surface which protects the fabric 1. It is to be understood that said layer 5 may comprise other wear-resisting materials.

I have found that if the product shown in Fig. 3 be laid over a joint in a roadway, that the excessive part of the impregnated material 3 shown at numeral 7 in Fig. 3, particularly on 20 warm days, functions as a lubricant which, when tangential thrust is applied to the surface 5, causes the strip as a whole to be readily displaced. A tangential thrust may come about, for instance, by means of a wheel which is skidding, or the traction of a driving wheel.

In view of the above, the excessive impregnating material 7 is scraped from the bottom of the fabric 1, as shown in Fig. 4. The result is a strip of impregnated fabric the lower surface of which 30 constitutes exposed fabric for application to and above joints. The amount of material removed from the bottom of the fabric 1 is, as shown in Fig. 4, enough to expose a substantial thread area of the fabric 1 so that the same may subsequently actually touch the roadway when the strip is applied thereto.

In order to facilitate transportation of the strips to the point of use, two of them are laid with the bottom or scraped fabric side face to face as shown in Fig. 5 and pressed together as shown at the right of said Fig. 5. The plural strips may then be wound or otherwise arranged for packaging and for transportation.

To prevent the asphalt of the protective layer 45 5 from becoming tacky, the surface of the layer 5 is treated with a talc. As to the lower, scraped face of the fabric, tackiness is not eliminated, because tackiness is desirable at this area after the layers are separated and immediately before 50 application, as indicated at the left in Fig. 5. The scraped, tacky surfaces being unexposed during transportation, offer no disadvantages.

Upon arrival at the point of use, the two composite strips (lettered A and B in Fig. 5) are pulled 55 apart, as shown at the left of Fig. 5. The separation causes the asphalt on the scraped side of the fabric to be slightly pulled out into the tooth-like structure shown at numeral 9 which, when the strip is applied to the roadway, effects 60 interlocking with the minute irregularities in said roadway, without forming a continuous lubricating film. The tooth-like particles extend into the recesses, permitting the fabric 1 to ultimately seat itself upon the higher portions surrounding the minute recesses in the roadway (Fig. 6). Under conditions where the impregnating asphalt is not scraped off as shown in Fig. 3, the 65 excess amount spaces the fabric away from the roadway, thus fully floating it and providing the undesirable warm weather lubricating qualities which are eliminated by permitting the fabric to touch the roadway, but so arranging what little asphalt is on the bottom of the fabric that 70 75 it forms a "tooth" in the roadway.

It will be understood that in laying the strip, small deviations in the joint are taken care of by choosing a suitable width of strip. Greater deviations of a more general character having long radii and curvatures, are taken care of by the plastic quality of the strip which may be bent in the plane of the strip, one way or the other, to follow the general curvature of the joint. The end joints are preferably of the lap type, but may, if desired, be of the butt type.

After laying the strip, it is tamped down, either by walking on it or otherwise, and thereafter the weight of the vehicles passing thereover continually forces it more and more compactly into the desirable leak-proof position flat against the material of the roadway and bridging the joint.

The material may be applied at any temperature. If it is applied while the temperature is low, a subsequent rise will cause the joints to become smaller and the strip to assume the bowed conformation such as shown in Fig. 6. It will bow downwardly, because of the traffic passing thereover.

If the strip is laid while hot, and subsequent cooling sets in, there is enough stretch in the material to take care of small variations, and if cooling is excessive, the strength of the material is enough to hold against the relatively large force required to slightly laterally slip the edges of the strip as the portions of the roadway adjacent to the joints separate. This process is not accompanied by leakage, because of the intimate character of the contact between the strip and the roadway. The force involved in this adjustment is greater than that caused by traffic and the latter will not cause slip. Furthermore, the traffic which passes over quickly fastens down the strip in its altered position. After adjustment has taken place for the coldest condition, thereafter further lateral adjusting slipping does not take place because subsequent heating causes the condition shown in Fig. 6.

From the above it will be seen that among the advantages of the invention are the following:

1. The strip effects a perfectly watertight covering which remains in the position relative to the joint at which it was placed at the time of application. It does not gradually work down into the joint and effect a sump for further gathering of moisture. No freezing of moisture can 5 take place within the joint to cause disintegration, nor can deterioration set in at the base of the joint.

2. The material adjusts itself to all temperature conditions without introducing leakage. Furthermore, it is of such a flexibility that it does not ultimately break due to fatigue. In this respect, it will be appreciated that the asphalt is a substance which, under all temperatures is of a plastic or flowing nature and thus tends constantly to correct by inflowing any incipient breakage.

3. The strip does not slip or skid from its position over the joint. It will hold tenaciously, even against abusive forces, such as the action of a skidding and/or locked wheel sliding thereover. However, under great enough forces of contraction of the road material it will adjust itself.

4. The material may be pre-fabricated under 70 factory conditions and applied with great simplicity under the adverse conditions met with on highways. It will be appreciated that the elimination of any complications in applying a substance to a joint for repair work is vital, because 75

of the requirement that traffic be not too much interfered with.

5. The product per se is simple in construction and may be economically made so that it is cheaper to the consumer, even with its advantages.

6. If, and when the material requires replacement, due to accidental mutilation or long service, the old strip may readily be removed by the introduction of a flat spade-like tool thereunder (with or without heat) and movement of the same along the strip, and application of a new strip.

It will be understood that the drawing is exaggerated in its dimensions in order to clearly bring out features of the invention and that actually the strip is thin enough so as to cause no inconvenience to traffic. It is of the order of one-eighth inch thick when laid.

7. In view of the above, it will be seen that the several objects of the invention are achieved and other advantageous results attained.

As many changes could be made in carrying out the above constructions without departing 5 from the scope of the invention, it is intended that all matter contained in the above description or shown in the accompanying drawing shall be interpreted as illustrative and not in a limiting sense.

0 I claim:

1. As an article of manufacture, a cover strip for joints in roadways and the like comprising a

strip of fabric impregnated with tacky asphalt in such manner that one surface of said fabric is substantially entirely covered with asphalt, while the other surface of said fabric is substantially all exposed, and free from asphalt, the asphalt, however, penetrating the interstices of said fabric in such manner that it presents a tacky surface for said second-named fabric surface, whereby said strip, when applied to a roadway, adheres thereto with the second-named fabric surface directly juxtaposing the roadway surface without substantial amounts of asphalt therebetween.

2. As an article of manufacture, a cover strip for joints in roadways and the like comprising a strip of fabric impregnated with tacky asphalt in such manner that one surface of said fabric is substantially entirely covered with asphalt, while the other surface of said fabric is substantially all exposed, and free from asphalt, the asphalt, however, penetrating the interstices of said fabric in such manner that it presents a tacky surface for said second-named fabric surface, whereby said strip, when applied to a roadway, adheres thereto with the second-named fabric surface directly juxtaposing the roadway surface without substantial amounts of asphalt therebetween, and a coating of protective material on said strip surmounting the asphalt on the first-named fabric surface.

WILLIAM C. FERGUSON.
